UNITED STATES PATENT OFFICE.

WILLIAM C. SHANLEY, OF DES MOINES, IOWA.

DEVICE FOR CONNECTING SUCTION PIPES TO TANKS AND OTHER RECEPTACLES.

Application filed February 21, 1921. Serial No. 446,652.

To all whom it may concern:

Be it known that I, WILLIAM C. SHANLEY, a citizen of the United States, residing at Des Moines, in the county of Polk and State 5 of Iowa, have invented certain new and useful Improvements in Devices for Connecting Suction Pipes to Tanks and Other Receptacles, of which the following is a specification.

10 This invention relates to devices for supporting a pipe in the manhole or opening of a tank or other receptacle containing a liquid, and particularly to means for supporting a suction pipe in the manhole or dome 15 of a tank car. An important feature of the invention consists in so connecting the suction pipe with the tank that the pipe has a fire-proof connection therewith so that inflammable gases cannot easily pass through 20 the device and flame cannot enter.

It is a common practice to unload tank cars by means of a suction pipe through the manhole of the tank dome and heretofore in practice such tanks have not been provided 25 with means for preventing the escape of inflammable gases or the entrance of flame.

According to my invention I provide means whereby the suction pipe may be introduced through the dome of the tank and 30 which are of such form that the pipe may be shifted or moved to a limited extent laterally without producing an opening which would permit the escape of gases or the entrance of flame. Such a device is used at an 35 unloading station where a suction pipe is located. When the suction pipe is withdrawn or when the tank car is in transit from a loading to an unloading station a cap or cover is provided which closes the suction 40 hole opening and thus protects the contents of the car.

Briefly stated, the device consists of a 45 cover for the dome having an elongated opening therein through which the suction pipe may be passed and wherein it has a lateral movement to a limited extent. Above the cover top having the elongated opening is arranged a sliding plate operating in guide rails and having a circular opening of 50 approximately the diameter of the suction pipe and through which the suction pipe extends. When the pipe is moved laterally the slide is correspondingly moved over the cover top having the elongated opening and the arrangement is such that the opening in 55 the cover top is not exposed in such manner

as to permit the escape of vapors or the entrance of flame. The means for closing the openings in the sliding plate and the cover top when the tank car is in transit consists 60 of a cap adapted to fit over the openings and provided with means for securely fastening it to the cover.

In the accompanying drawings,

Figure 1 is a perspective view of a portion 65 of a tank car, the dome of which is equipped with some of my improvements;

Figure 2 is a detail view in vertical section of the dome with some of my improvements applied;

Figure 3 is a plan view of the same;

Figures 4 to 6 inclusive illustrate that form 70 of my invention in which a cover is provided for closing the dome tightly when the car is in transit or when the suction pipe is removed;

Figure 4 is a perspective view with the several parts separated;

Figure 5 is a plan view of the assembled 75 parts;

Figure 6 is a plan view of the dome cover;

Figure 7 is a plan view of a plate secured 80 to the dome cover and carrying a sliding plate having an opening to receive the suction pipe.

Figure 8 is a plan view of the cap.

It will be observed that in Figures 4 to 8 85 inclusive the devices shown in Figures 1 to 3 inclusive are employed in connection with other elements.

Referring first to Figs. 1 to 3, A indicates the dome of a tank car B. C indicates a cover for the dome, which cover is formed with an elongated opening D. A plate F, having a circular opening f, is adapted to 90 slide in guide rails E, attached to the cover C. The suction pipe H is adapted to extend through the opening f and also through the opening D and into the tank B. In this way a fire-proof connection is made between the suction pipe and the tank and provision is made for allowing a limited lateral movement of the pipe in the tank. When the suction pipe is withdrawn the sliding plate may be drawn to one side and to such extent 95 as to bring the circular opening f beyond one end of the elongated opening D.

I prefer, however, to employ special means for closing the openings when the suction pipe is removed and these devices are shown 100 in Figures 4 to 8 inclusive. In this case the dome A has a raised portion a, on which

rests a cover H' , having bolt holes h in it to receive bolts a^2 , which also pass through holes a' in the dome. The cover H' is in this way permanently attached to the dome 5 and said cover is formed with an elongated opening m similar to the opening D , above described. The cover carries rails m' which serve to guide the slide N , which has a central opening n to receive the suction pipe. 10 The slide N may be operated in the same manner as the slide F in Figure 3. The suction pipe may be passed through the hole n and through the elongated opening h and the pipe may be shifted laterally while in the 15 tank to a considerable extent. When the pipe is withdrawn it is desirable to tightly close the openings, especially when the tank is filled with volatile liquid. I therefore provide the cover H' with bolts O , which 20 have a threaded connection with the cover at o , extend through the cover and carry nuts o' . P indicates a cap, preferably of the shape shown, having recesses p to receive the bolts O , and these bolts carry clamping devices Q which, when the parts are assembled, pass over the bolts O and are held thereon by nuts q . The arms of the clamping devices engage the cap P and the cover H' and hold the cap firmly on the cover in such manner as to enclose the sliding plate 25 N and protect the opening through the cover from danger of fire.

It will be understood that the cover plate H' is permanently attached to the dome A . 30 When it is desired to insert a pipe into the tank the cap P , the clamps Q and the nuts q are withdrawn, thus exposing the sliding plate N . The suction pipe may be inserted and moved laterally to a limited extent, as 35 before described. When the suction pipe is withdrawn the cover P is applied in such manner as to cover the openings n and m , as well as the slide and the guides and then the clamps Q are applied to the bolts O and the 40 nuts q screwed home. By these improvements provision is made for preventing many losses which have heretofore occurred, due to the absence of proper provision for preventing ignition of inflammable gases 45 rising from volatile liquids.

I claim as my invention:

1. A cover for a receptacle provided with an elongated pipe-receiving opening extending through it from top to bottom, a 55 sliding plate supported on the cover and having a circular opening completely surrounded by the body of the plate which covers the elongated opening on opposite sides of said circular opening, and which is movable from end to end of the elongated opening, and parallel guides for said plates.
- 60 2. A cover for a receptacle provided with

an elongated pipe-receiving opening, a plate mounted to slide on the cover and having a circular opening midway between its opposite ends to receive a suction pipe and which covers said elongated opening on opposite sides of said circular opening, and parallel guides for said plate. 65

3. The combination with the cover of a receptacle having an elongated pipe-receiving opening of parallel guide rails attached to the cover and spaced apart from end to end, a sliding plate mounted in said guides having a circular opening and a suction pipe 75 extending through the openings in the cover and in the plate.

4. The combination with a suction pipe of a receptacle having a cover provided with an elongated opening through which the pipe extends, a sliding plate supported on the cover above the elongated opening therein, and having a circular opening completely surrounded by the body of the plate through 80 which the pipe extends and means for covering the openings in the cover and in the plate when the suction pipe is withdrawn. 85

5. The combination with a suction pipe, of a receptacle having a cover provided with an elongated opening, a sliding plate supported on the cover above the elongated opening therein and having a circular opening movable from end to end of the elongated opening with the pipe when the plate is adjusted on the cover, said plate having 90 closed portions on opposite sides of the circular opening for completely closing the elongated opening when the circular opening in the plate is moved beyond either end of the elongated opening. 100

6. A receptacle having an opening closed by a removable cover formed with an elongated opening in combination with a sliding plate supported on the cover and having a circular opening to receive a suction pipe, a cap for covering the openings in the sliding plate and in the cover plate, and means for securing the cap to the cover plate. 105

7. The combination with the manhole of a receptacle of a cover plate bolted thereto and having an elongated opening in it, guide rails secured to the cover plate, a plate sliding in said guide rails and having a circular opening in it through which the suction pipe extends, bolts attached to the cover plate, a 110 cap for covering the openings in the sliding plate and in the cover plate and which is formed with recesses through which said bolts extend, and clamping devices carried by the bolts for holding the cap in place on the 115 cover plate. 120

In testimony whereof, I have hereunto subscribed my name.

WILLIAM C. SHANLEY.
